& Rubber Company, Conshohocken, Pa., a corporation
of Ohio

Filed Apr. 27, 1970, Ser. No. 22,656

Term of patent 14 years

Int. Cl. D12—14

U.S. Cl. D90—20

FIG. 1

FIG. 2

FIG. 1 is a perspective view of a tire showing my new design, it being understood that the design is repeated throughout the circumference of the tire, the opposite side being substantially the same as that shown; and

FIG. 2 is an enlarged fragmentary plan view of the tire shown in FIG. 1.

I claim:

The ornamental design for a tire, substantially as shown and described.
